DESIGN FOR A HAND MIRROR

Albert Weewetzer, Elgin, Ill., assignor to Illinois
Watch Case Company, Elgin, Ill., a corporation
of Illinois

Application July 5, 1935, Serial No. 57,531

Term of patent 3½ years

all whom it may concern:
Be it known that I, Albert Weewetzer, a citizen of the United States, residing at Elgin, in the County of Kane and State of Illinois, have invented a new, original, and ornamental Design for a Hand Mirror, of which the following is a specification, reference being had to the accompanying drawing, forming part thereof.

Figure 1 is a rear elevational view of a hand mirror, showing my new design; and Figure 2 is a side view of the same.

I claim:

The ornamental design for a hand mirror, as

ALBERT WEEWETZER.
